UNITED STATES PATENT OFFICE.

THOMAS CARNEY, OF DAYTON, OHIO, ASSIGNOR, BY MESNE ASSIGNMENTS,
TO NATIONAL CASH REGISTER COMPANY, OF JERSEY CITY, NEW JERSEY.

CASH-REGISTER.

SPECIFICATION forming part of Letters Patent No. 683,877, dated October 1, 1901.

Application filed April 30, 1898. Serial No. 679,324. (No model.)

To all whom it may concern:

Be it known that I, THOMAS CARNEY, a citizen of the United States, residing at Dayton, in the county of Montgomery and State of Ohio, have invented certain new and useful Improvements in Cash-Registers, of which I declare the following to be a full, clear, and exact description.

This invention relates to improvements in cash-registers, and has more particular relation to that class of machines which print a record or detail strip of the transactions.

One of the several objects of the invention is the application of an improved detail-strip printer to the type of machine patented to me March 19, 1895, and numbered 536,015.

The invention consists of certain novel constructions, combinations, and arrangements of parts, all of which will be hereinafter more particularly set forth and claimed.

In the accompanying drawings, forming part of this specification, Figure 1 represents a side elevation of the devices embodying my invention applied to a machine of the type described and illustrated in the aforesaid Letters Patent. Fig. 2 represents a top plan view of the same. Fig. 3 represents a vertical transverse section through the said machine. Fig. 3^a represents a detail side elevation, partly in section, of the actuating parts for the five-cent-key bank; and Fig. 4 represents an enlarged detail view of the construction of the sleeves and pinions for actuating the printing-wheels.

In the said drawings, 1 represents the frame of the machine, and 2 the printing-hammer or platen. The construction and operation of the keys, registering mechanism, and indicators are substantially the same as that described in the above-mentioned patent, and attention are therefore called to the same for a detail description of said devices. One exception to the above statement is that the keys are arranged in three banks, representing, respectively, a five-cent bank, a tens-of-cents bank, and a units-of-dollars bank. The single key 6 of the five-cent bank is arranged to operate a movable frame 7, while each of the keys 8 and 9 of the tens-of-cents bank is arranged to operate a movable frame 10 in

practically the same manner as described in the aforesaid Letters Patent with a few exceptions hereinafter noted. The units-of-dollars keys 11 are arranged to actuate a movable frame 12, similar to the frame 10 and adapted to be operated in substantially the same manner. Each of the frames 7, 10, and 12 is connected to one of a series of operating rack-segments 13, 14, and 15, so as to operate the same and impart a greater or less movement, according to the value of the key pressed. Each of the keys 8, which represent the uneven multiples of five, has an equal actuating value with relation to the frame 10 as the preceding key 9, representing one of the even multiples of five, and will thus only move said frame to an equal extent. It is therefore necessary to actuate both of the frames 7 and 10 upon one of the keys 8 being depressed, and to accomplish this result I provide a journaled frame 16, mounted upon the pivot-shaft of the keys. This frame is provided on its under side with a plurality of spaced pendent lugs 17 so located as to lie directly over the inner portions of the keys 8. By this structure when any one of the keys 8 is depressed the rear portion of the same contacts with the lug 17, lying above it, and thus raises and rocks the frame 16. This action of the frame causes a rearwardly-extending arm 18, mounted thereon, to be raised simultaneously therewith, and thus operate a vertical bar 19^a, pivotally connected thereto, said bar 19^a operating the frame 7 in the manner of the usual bars described in said patent. The five-cent key, to which the bar 19^a properly belongs, is not positively connected thereto, but is adapted to strike one of the pendent projections 17 when operated, and thus rock the frame 16 and actuate the frame 7; otherwise the key 6 is practically the same as the other keys both in construction and operation.

By means of the above construction the five-cent-key frame 7 is operated upon the operation of any of the keys 8, as well as the key-frame proper, 10, of said keys, and the registration is thus recorded upon both the five-cent counter-wheel and the tens-of-cents counter-wheel. Any operation of the keys 9

will simply result in the movement of the frame 10, as none of the projections 17 are located above said keys.

Each of the rack-segments 13, 14, and 15 meshes with one of a series of pinions 19, 20, and 21, which are respectively connected to the printing-wheels 22, 23, and 24 as follows:

The pinion 19 is loosely mounted upon a shaft 25 and held in position thereon by a collar 25^a and is provided with a sleeve 26, having a notch 27 formed therein for the reception of a lug 28, mounted upon a collar 29, which is secured rigidly to the said shaft. The lug 28 is of less width than the notch 27, into which it projects, whereby in the operation of alining the printing-wheels just before the printing operation the shaft 25 and the printing-wheel 24, fast thereon, may be given a limited movement entirely independent of the pinion 19. This means to enable the exact alining of the types on the printing-wheels is a special feature of my present invention, because, contrary to many devices of this kind, in my invention the printing-wheels are always in positive engagement with the actuating-segments. The pinions are thereby rigidly held when the segments are at rest after having completed their movement, and the printing-wheels are positively moved by the actuating devices, yet the connection is sufficiently flexible to permit of an exact and proper alinement. The pinions 20 and 21 are also constructed as above described and have their respective collars mounted on nested sleeves 29^a, which surround the shaft 25 and support the several remaining printing-wheels. By means of the above-described connections the printing-wheels 22, 23, and 24 are moved through the medium of the segmental racks 13, 14, and 15 to an extent equal to the values of the keys pressed. In order to bring the desired characters of the printing-wheels into proper alinement with the platen 2, each of said wheels is provided with a star-wheel 30, which is arranged to be engaged by one of a series of alining arms or pawls 31, formed on a pivoted frame 32. This frame is provided with an operating-arm 33, having a nose 34 formed on its lower end and normally forced into engagement with a cam-wheel 35 by a coil-spring 36, which latter is mounted in a socketed lug 37, secured to the frame and engages the side of said arm. The said cam-wheel 35 is fast upon a revolution-shaft 38, which is rotated upon the operation of a key by a double-acting loop-rack, substantially the same as described in the before-mentioned patent. The endless inking ribbon or tape 39 extends directly under the printing-wheels and passes about antifriction-rollers 40, 41, and 42 and also about a feeding-roller 43, which latter is covered with a friction-felt to prevent slipping of the ribbon. This felt is normally saturated with a suitable ink and forms a source of ink-supply for the ribbon, so that the same will be continually reinked as it

passes over said roller. This roller 43 is provided with a gear-wheel 44, meshing with an intermediate gear 45, which in turn meshes with a gear 46, journaled on the frame. The said latter gear carries a ratchet-wheel 47 and a spool 48, the latter being arranged to receive the detail-strip 49 and draw it forward after each printing operation. The forward step-by-step movement of the spool is effected by means of a spring-pressed hook-pawl 50, which is mounted upon an arm 51, fast to the extended journal end 52 of the universal or key-coupling bar 70 of the machine and receives motion therefrom. A spring-pressed pawl 53^a is also mounted on the frame and engages the ratchet-wheel 47 to prevent any backward movement of the same. The before-mentioned strip 49 passes over two spaced supporting-bars 53 and 54 and under the ribbon 39 and is fed from a supply roller or spool 55. As the inking-ribbon may become stretched by constant use, I provide means for keeping it under tension at all times, and thus avoiding any slipping on the feed-roller. This tension device comprises a pivoted yoke 56, in which is journaled a heavy antifriction-roller 57, arranged to rest upon the inking-ribbon, and thus by its gravitating action keep the ribbon taut at all times. The platen or printing-hammer 2, before mentioned, is preferably formed of rubber or other resilient material and is mounted on a pivoted arm 58, which is normally forced upward by a spring 59, mounted under the same. Said arm is depressed against the tension of the spring 59 by a cam 60, mounted on the revolution-shaft 38 and engaging a nose 61, formed on said arm. The construction of the cam 60 is such that the arm 58 is depressed gradually and then allowed to suddenly fly back, so as to secure a hammering or tapping stroke of the platen. The outer end of the arm 58 is provided with a spring-pressed plunger-rod 62, which is adapted to contact with the bar 53. By this means the platen is first thrown up against the detail-strip with the aforesaid tapping stroke and then positively forced away from the same by the plunger-rod and its spring.

It will be noticed that the printing devices are at all times in positive connection with the registering segments 13, 14, and 15, which form part of the operating mechanism.

For the purposes of the claims I have referred to all of the operating parts from the keys to the registering segments as the "operating mechanism," and it will be readily seen that the keys are alternately brought into and thrown out of co-operative engagement with the intermediate devices between them and the printing devices upon each operation of the machine.

Having thus described my invention, what I claim as new, and desire to secure by Letters Patent, is—

1. In a cash-register the combination with the operating mechanism, the type-carriers

which are in positive engagement with the operating mechanism, an alining means arranged to be operated while the type-carriers and the operating mechanism are in such

5 positive engagement and a flexible connection between the type-carriers and the operating mechanism whereby the former may have limited movements independent of their operation through said movable connection, 10 substantially as described.

2. In a cash-register the combination with the operating mechanism, of a shaft surrounded by one or more hollow shafts, type-carriers in positive engagement with the operating 15 mechanism through said shafts, means for setting said type-carriers by the initial movement of the operating mechanism, means for moving the record-strip against the type-carriers, an alining mechanism for the type-carriers and a flexible connection with which 20 said shafts are provided whereby the type-carriers are first positively moved approximately to printing position by the operating mechanism and then alined independently of 25 their movements through said movable connection and prior to the operation of the devices for pressing the record-strip against the type-carriers, substantially as described.

3. In a cash-register, the combination with 30 a series of keys, of a printing mechanism, a record-strip-winding roller, a ratchet-wheel on said roller, a movable member common to all of the keys and having an extended journal end, a rigid arm on said journal end and 35 an operating-pawl mounted on said arm and engaging said ratchet-wheel.

4. In a cash-register, the combination with an operating mechanism, of printing devices arranged to be operated thereby, alining 40 means for said devices, and means for connecting the operating mechanism and the printing devices but allowing the latter to be alined independently of such connection.

5. In a cash-register, the combination with 45 a series of keys, of printing devices, alining means for said devices, and means connecting said keys and printing devices including notched collars and collars having projections

which enter said notches, the construction being such that the printing devices may be 50 alined independently of their regular connection with the keys.

6. In a cash-register, the combination with an operating mechanism, of printing devices arranged to be operated thereby, alining 55 means for said devices, and means for establishing a connection between the operating mechanism and the printing devices but allowing the latter to be alined independently of 60 said connection with the operating mechanism.

7. In a cash-register the combination with an operating mechanism of a plurality of printing - wheels, alining devices for said wheels connected to the moving parts of the 65 machine, and means connecting the operating mechanism with the printing-wheels for moving the latter but at the same time allowing them to be alined independently of such connection. 70

8. In a cash-register the combination with a plurality of operating - racks, of a shaft, nested sleeves mounted over said shaft, collars fast on said shaft and sleeves and each formed with a projection, pinions meshing 75 with the racks and each formed with a recess to receive its respective projection, printing-wheels mounted on said shaft and sleeves and alining devices for said wheels.

9. In a cash-register, the combination with 80 a series of keys, of a printing mechanism, a record-strip-winding roller having a ratchet-wheel, an inking-ribbon, a feeding-roller for the same, means connecting said feeding-roller with the winding-roller so that they 85 move simultaneously, a movable member common to all of the keys, an arm mounted rigidly on said member and a pawl mounted on said arm and engaging said ratchet-wheel.

In testimony whereof I affix my signature 90 in the presence of two witnesses.

THOMAS CARNEY.
